UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER.

1,258,010.

Specification of Letters Patent.

Patented Mar. 5, 1918.

Application filed April 18, 1917. Serial No. 162,966.

To all whom it may concern:

Be it known that I, HENRY D. JAMES, a citizen of the United States, and a resident of Edgewood Park, in the county of 5 Allegheny and State of Pennsylvania, have invented a new and useful Improvement in Circuit-Interrupters, of which the following is a specification.

My invention relates to circuit interrupters and particularly to circuit interrupters of the normally-inclosed type.

One object of my invention is to provide means for so relieving the pressure within the circuit-interrupter casing, under predetermined conditions, that the arc, which is drawn when the interrupter opens, is precluded from taking an abnormal course.

Another object of my invention is to provide means for so positively opening the 20 interrupter casing, prior to the final interruption of the circuit, that the arc may be projected through the opening in the casing.

A further object of my invention is to 25 provide a device of the above-designated character that shall be cheap to construct and effective in its operation.

In practising my invention, I provide stationary and movable contact members that 30 are mounted in a casing having a door therein that is adjacent to the contact members. The door is provided with a cam portion that is adapted to be engaged by a projection on the movable contact member 35 of the interrupter. Thus, when the movable contact member is actuated, the projection engages the cam portion of the door and forces the door open a sufficient interval of time before the arc is broken to permit 40 the same to be projected out through the opening and to preclude the arc from jumping between points that are located at a relatively great distance from the main contact members of the interrupter.

45 Figure 1 of the accompanying drawings is a side view, partially in section and partially in elevation of a portion of a circuit interrupter embodying my invention, and Fig. 2 is a side view, partially in elevation 50 and partially in section, of a circuit interrupter embodying a modified form of my invention.

The circuit interrupter embodying my invention comprises, in general, a casing 1 55 having a stationary contact member 2 and

a movable contact member 3 mounted therein and a spring-restrained door 4 that is disposed adjacent to the contact members 2 and 3.

The stationary contact member 2 is 60 mounted on a bracket 5 that is supported from the upper portion 6 of the casing 1, and the movable contact member 2 is pivotally mounted on a lever arm 7 that is mounted on a bracket 8 which is supported 65 on the upper portion 6 of the casing 1. The brackets 5 and 8 are operatively connected to terminal members 9 and 10 to facilitate securing conductors 11 and 12 thereto. An actuating device (not shown) is 70 operatively connected, through a connecting means 13, to the lever arm 7. A blow-out coil 14 is disposed adjacent to the contact members 2 and 3 for the purpose of extinguishing the arc that is drawn there- 75 between. The contact members 2 and 3 are provided with arcing tips or horns 15 and 16 that are adapted to force the arc outwardly when the contact members are disengaged.

80 The door 4 is provided with a spring 17 for normally restraining it in its closed position and has a cam portion 18 on its inner side that is adapted to be engaged by a projection 19 which is mounted on the lever arm 85 7. During the closing movement of the member 3, the projection 19 so engages the cam portion 18 that the door 4 is opened a predetermined period of time before the contact members are engaged. Similarly, 90 when the contact member 3 is moved downwardly, the projection 19 engages the cam portion 18 to cause the door 4 to be opened a sufficient time before the arc, that is drawn between the contact members 2 and 3, is 95 finally broken, for the purpose of so relieving the gaseous pressure in the casing 1 that the arc will not be drawn between the supporting brackets 5 and 8 and to permit it to be forced out through the opening in the 100 casing 1 that is provided when the door 4 is moved to its open position.

In Fig. 2 of the drawings, a member 20 is mounted on the lever arm 7 and has a pawl or cam member 21 mounted at its outer end 105 and normally-restrained in position by a spring 22. When the device shown in Fig. 2 is used, the closing operation of the switch merely causes the member 21 to be turned to such position that it does not move the 110

2
door 4. However, when the movable contact member 3 is moved downwardly the member 31 so engages the cam portion 18 of the door 4 that the door is forced open a 5 predetermined interval of time before the arc that is drawn between the contact members 2 and 3 is broken. Thus, the arc is forced outwardly by the blow-out coil 14 and the gaseous pressure within the casing 1 10 is so reduced that the arc is precluded from jumping between points that are located at a relatively great distance from the contact members 2 and 3.

I do not limit my invention to the particular structure illustrated, as it may be variously modified within the spirit and scope of the invention as set forth in the appended claims.

I claim as my invention:

- 20 1. The combination with a switch, of a casing therefor having a door adjacent to the switch, and means mounted on the movable member of the switch for opening the door for an instant before the switch is opened.
- 25 2. The combination with a switch, of a casing therefor having a door adjacent to the switch, and means mounted on the movable member of the switch for opening the door for an instant before the switch is opened and closed.
- 30 3. The combination with a switch, of a casing therefor having a normally closed door adjacent to the switch, and means actuated by the movable member of the switch for forcing the door open when the switch is opened.

4. The combination with a switch, of an inclosing casing therefor, a door hinged to the casing having a cam portion thereon, 40 and a projection on the movable member of the switch for so engaging the cam portion of the door that the door is opened just before the switch is completely opened.

5. The combination with a switch, of an 45 inclosing casing therefor, a door hinged to the casing and having a cam portion thereon, and means on the movable member of the switch for so engaging the cam portion of the door that the door is opened just before 50 the switch is completely actuated.

6. The combination with a switch, of a casing therefor, a door for the casing disposed adjacent to the contact members of the switch, and means mounted on the movable member of the switch for so opening the door that the pressure within the casing is relieved before the switch is entirely opened.

7. The combination with a switch, of an 60 inclosing casing therefor, and means actuated by the movable member of the switch for opening a portion of the casing just before the switch is opened.

8. The combination with a switch, of an 65 inclosing casing therefor, and means actuated by the movable member of the switch for relieving the pressure within the casing before the switch is completely opened.

In testimony whereof, I have hereunto 70 subscribed my name this 30th day of March, 1917.

HENRY D. JAMES.
